UNITED STATES PATENT OFFICE

108,024

DESIGN FOR A COMBINATION BLOTTER AND PAD HOLDER FOR DESKS

Gloria Stone, Buffalo, N. Y.

Application June 23, 1936, Serial No. 63,440

Term of patent 3½ years

To all whom it may concern:

Be it known that I, Gloria Stone, a citizen of the United States, residing at Buffalo, in the county of Erie and State of New York, have invented a new, original, and ornamental Design for a Combination Blotter and Pad Holder for Desks, of which the following is a specification, reference being had to the accompanying drawing, forming part thereof.

The characteristic feature of my design resides in the configuration of the extension flap as shown.

I claim:—

The ornamental design for a combination blotter and pad holder for desks as shown and described.

GLORIA STONE.
